(57) **CLAIM**

(21) Appl. No.: **29/198,780**

The ornamental design for a fifth wheel landing jack leveling device, as shown and described.

(22) Filed: **Feb. 5, 2004**

DESCRIPTION

(51) LOC (8) Cl. **12-05**

FIG. 1 is a top plan view of my fifth wheel landing jack leveling device, showing the new design;

(52) U.S. Cl. **D34/31**

FIG. 2 is a front elevational view thereof;

(58) Field of Classification Search ..... D34/28, D34/31, 32, 35; 254/126, 2 R, 93 H, 134, 254/420, DIG. 1, 423, 424

FIG. 3 is a right side elevational view thereof, the opposite side comprising a mirror image;

See application file for complete search history.

FIG. 4 is a bottom plan view thereof;

(56) **References Cited**

FIG. 5 is a left, frontal isometric view thereof;
